(57) **CLAIM**

We claim the ornamental design for a carburetor metering body and bowl vent, as shown and described.

DESCRIPTION

FIG. 1 is a front perspective view of a carburetor metering body device, showing the claimed design.

FIG. 2 is a rear perspective view of the carburetor metering body of FIG. 1.

FIG. 3 is a front elevation view of the carburetor metering body of FIG. 1.

FIG. 4 is a rear elevation view of the carburetor metering body of FIG. 1.

FIG. 5 is a right side view of the carburetor metering body of FIG. 1.

FIG. 6 is a left side view of the carburetor metering body of FIG. 1.

FIG. 7 is a top plan view of the carburetor metering body of FIG. 1.

FIG. 8 is a bottom plan view of the carburetor metering body of FIG. 1.

FIG. 9 is a perspective view of a bowl vent device to be used with the carburetor metering body device of FIG. 1, showing the claimed design.

FIG. 10 is a second perspective view of the bowl vent device of FIG. 9.

FIG. 11 is a front elevation view of the bowl vent device of FIG. 9.

FIG. 12 is a rear elevation view of the bowl vent device of FIG. 9.

FIG. 13 is a right side view of the bowl vent device of FIG. 9.

FIG. 14 is a left side view of the bowl vent device of FIG. 9.

FIG. 15 is a top plan view of the bowl vent device of FIG. 9.

FIG. 16 is a bottom plan view of the bowl vent device of FIG. 9.

FIG. 17 is a front elevation view of the carburetor metering body of FIG. 1, with the bowl vent device of FIG. 9, showing the claimed design.

FIG. 18 is a rear perspective view of the carburetor metering body of FIG. 17.

FIG. 19 is a front elevation view of the carburetor metering body of FIG. 17.

FIG. 20 is a back elevation view of the carburetor metering body of FIG. 17.

FIG. 21 is a right side view of the carburetor metering body of FIG. 17.

FIG. 22 is a left side view of the carburetor metering body of FIG. 17.

FIG. 23 is a top plan view of the carburetor metering body of FIG. 17.

FIG. 24 is bottom plan view of the carburetor metering body of FIG. 17.

FIG. 25 is a partial sectional view, in perspective, of the carburetor metering body of FIG. 17, as viewed along line 25-25; and,

FIG. 26 is a partial sectional view, in perspective, of the carburetor metering body of FIG. 18, as viewed along line 26-26.

The broken lines used in the figures are for illustrative purposes only and form no part of the claimed design.
